WRAPPING-MACHINE.

1,115,407.

Specification of Letters Patent. Patented Oct. 27, 1914.

Application filed August 9, 1913. Serial No. 783,921.

To all whom it may concern:

Be it known that we, HILARIO DE ESCOBALLES, a citizen of the Island of Porto Rico, and a resident of the borough of Manhattan, in the city of New York, county and State of New York, and FRANCIS P. AMPUDIA, a citizen of Spain, and a resident of the borough of Manhattan, in the city of New York, county and State of New York, have invented a certain new and useful Improvement in Wrapping-Machines, of which the following is a specification.

This invention relates to mechanism for folding wrappers around articles which are successively passed through the machine.

The object of the invention is to simplify such mechanism, and to provide means for wrapping said articles in an efficient manner.

The invention consists of endless chains carrying a series of receptacles adapted to receive partially wrapped articles and means for imparting intermittent movements thereto. A two-part plunger is provided, one part thereof having reciprocating movement in range with one of said receptacles, whereby a partially wrapped article is forced into said receptacle. The second part of said plunger is adapted for reciprocating movement through another one of said receptacles, whereby a partially wrapped article therein is forced out and into a receiving channel. During return movement of said two-part plunger, mechanism for applying paste to a wrapper flap of a partially wrapped article in another one of said receptacles, and for folding wrapper flaps of said article in the receiving channel are simultaneously actuated. During the time said chains are moving, wrapper folding mechanism which is actuated by said means for imparting intermittent movements to said chains, causes said wrapper flaps of the article in the receiving channel to be further folded upon the article. Said means for imparting intermittent movements to said chains also actuate rollers for feeding paper from a supply roll. During the time said feed rollers remain stationary, a wrapper is cut from said paper, by means of a pair of scissors which are actuated by a cam forming part of the machine.

In the accompanying drawings: Figure 1

is a sectional side elevation of the machine. Fig. 2 is a horizontal section on the line 55 II-II of Fig. 1. Figs. 3 to 9 inclusive are perspective views showing different stages of folding of the wrapper upon the article. Fig. 10 is a transverse section of the line 60 X-X of Fig. 1. Fig. 11 is a transverse section on the line XI-XI of Fig. 1. Fig. 12 shows the paste applying, and wrapper folding mechanism, in a position different from that shown in Fig. 1.

A horizontal driving shaft 1 is journaled 65 in bearings 2 on the frame 3 of the machine. A lever 4 is pivoted at 5 on the frame 3. One arm of lever 4 is provided with a roller 6 which engages a cam 7 on shaft 1. The other arm of lever 4 is connected by links 8 70 to a plunger 9 which is adapted for horizontal reciprocating movement in guides 10.

Secured to shaft 1 is a bevel gear wheel 11 in mesh with a bevel gear wheel 12 which is secured to the lower end of a vertical shaft 75 13. Secured to vertical shaft 13 is a gear wheel 14, in mesh with a gear wheel 15 which is journaled upon a stud shaft 16 extending downward from the frame 3. Forming part of gear wheel 15 is a horizontal 80 disk 17, having an upwardly extending pin 18. During part of the rotation of gear wheel 15, pin 18 engages one of a series of six slots 19 formed in a horizontal disk 20, which disk is secured to a vertical shaft 21. 85 During the engagement of pin 18 with any one of the slots 19; the disk 20 and therefore the shaft 21 will move one-sixth of a revolution. During the time pin 18 is out of engagement 90 with the slots 19; the disk 20 and shaft 21 will ride against a concave surface 23 formed on the edge of disk 20, which will cause the disk 20 and shaft 21 to be held stationary 95 during the time pin 18 is out of engagement with the slots 19.

Secured to vertical shaft 21 is a bevel gear wheel 24 which is in mesh with a bevel gear wheel 25 on a horizontal shaft 26. To the upper end of vertical shaft 21 is secured a 100 bevel gear wheel 27 in mesh with a smaller bevel gear wheel 28 which is secured to a horizontal shaft 29. Secured to horizontal shaft 29 is a bevel gear wheel 30 in mesh with a smaller bevel gear wheel 31, which is secured to a horizontal shaft 32. It will be 105

evident that the intermittent movements imparted to vertical shaft 21 as has been described, will be transmitted to the horizontal shaft 26 by means of the gears 24 and 25, and also to the horizontal shafts 29 and 32, by means of the corresponding gears 27—28 and 30—31.

Secured to shaft 32 is a roller 33 and a gear wheel 34. Gear wheel 34 is in mesh 10 with a gear wheel 35 which is secured to a shaft 36. Secured to shaft 36 is a roller 37, the shaft 36 being journaled in movable bearings 38 which are pressed by a spring 39, so that the roller 37 will maintain a 15 yielding pressure against the paper 40 which is passed between the rollers 33 and 37. Said rollers serve to feed the paper downward in a chute 41, and between scissors blades 42 and 43, a distance equal to the 20 length of a wrapper below said scissors blades. It will be evident that this feed of paper will occur only during rotation of the shaft 21. The stationary scissors blade 42 is secured to a fixed rod 44 and the movable 25 blade 43, pivoted upon the rod, is held against the stationary blade by means of the spring 45. The arm 46 of movable blade 43 is provided with a roller 47 which engages a cam groove 48 formed in a wheel 49 secured to the upper end of vertical shaft 13. The cam groove 48 is so shaped that its action upon the movable scissors blade 43 is such that after feed rollers 33 and 37 have 30 ceased feeding the paper 40, the cam will cause movement of the blade 43, causing the wrapper blank 50 to be cut from the paper 40, which paper is fed from a supply roll indicated in Fig. 1. The wrapper blank 50, shown by a dotted line in Fig. 1, comes to 35 rest upon supports 51.

Secured to horizontal shaft 26 are chain wheels 52 and 53, over which ride corresponding endless chains 54 and 55. The endless chains 54 and 55 also ride over corresponding chain wheels 56 and 57 which are secured to a horizontal shaft 58.

Between chains 54 and 55 and secured to links thereof are a series of receptacles 59, for partially wrapped articles, which receptacles are placed at distances apart equal to the amount of travel which is imparted to said chain during each of the intermittent movements of shaft 26. The vertically moving portions of chains 54 and 55, extending 50 from chain wheels 52—53 to chain wheels 56—57, travel in guides 60 which are secured to the frame 3. Each end of the receptacles 59, is secured to a single link of chains 54 and 55, and, owing to the fact that said 55 chains travel in the fixed guides 60, the receptacles maintain a uniform position during their vertical travel. The receptacles 59 are each provided with movable walls 61 which are pressed by springs 62, so that 60 the walls maintain a yielding pressure upon

the wrapper of an article. The walls 61 are provided with bolts 63 which extend out through walls of the receptacle 59 and nuts 64 fitting the free end of the bolts, serve to limit the inward movement of walls 61 by 70 means of the springs 62.

An article 65 to be wrapped is placed between the plunger 9 and the wrapper blank 50. Forward movement of the plunger will 75 force the article and the wrapper between an upper stationary folder 66 and a lower stationary folder 67, causing the wrapper to be folded upon the article in the manner shown in Fig. 3. The forward movement of plunger 9 is sufficient to force the article and partially folded wrapper into a receptacle 59 which is secured to the portions of said chain resting in guides 60, and which travel upward when the movements of said chains occur.

Forming part of plunger 9 is a plunger extension 68, which is in range with a receptacle 59 secured to the portions of said chains resting in guides 60, and which travel downward when the movements of said chains occur. Plunger extension 68 is fixed to plunger 9 by means of an angularly shaped part 69 which is supported in a guide 70. The forward end of plunger extension 68 is close to said receptacle 59 in range 90 therewith, so that, simultaneous with the forcing of said article and wrapper into a receptacle 59 by forward movement of plunger 9 the plunger extension 68 will travel through said receptacle 59 in range 95 therewith, and into a receiving channel 71. After return movement of plunger 9 and plunger extension 68 occurs, the movement of shaft 26 will occur, causing said receptacles 59 to be moved out of range with said 100 plungers, said plungers remaining stationary long enough to permit other receptacles to be moved into range therewith. During successive movements of said plungers and receptacles, the partially wrapped articles 105 forced into the receptacles which are secured to the portions of chains traveling upward and over chain wheels 52 and 53 will come to rest in the position shown in Fig. 4, and with the wrapper flap 72 resting upon a support 73, as shown in Fig. 1. When this occurs, a paste receptacle 74 secured to arms 75 which are pivoted at 76, is moved from the position shown in Fig. 1 to the position shown in Fig. 12. During this movement, 110 a ratchet wheel 77 takes against a spring pressed pawl 78, causing rotation of said ratchet wheel and a shaft 79 to which said ratchet wheel is secured. Shaft 79 is journaled in the paste receptacle 74 and has a 115 roller 80 secured to it, which roller revolves in paste 81 within the receptacle and carries said paste out through an opening 82, so that, when the receptacle occupies the position shown in Fig. 12, paste will be applied 120 125 130

by the roller 80 to the wrapper flap 72, as shown at 83 in Fig. 4. An angular extension 84 of one of the arms 75 is provided with a slot 85 in which rides a pin 86 extending laterally from a rod 87 which has vertical reciprocating movement in a guide 88. The lower end of rod 87 is connected by links 89 to one end of a lever 90 which is pivoted at 91 to the frame 3. The other end of lever 90 is provided with a roller 92 which engages a cam groove 93 found in a wheel 94 on shaft 1, by which it is actuated. When another movement of the receptacle 59 occurs, the wrapper flap 72 to which paste has been applied will be moved downward against a stationary folder 95, causing said wrapper flap to be folded to the position shown by a dotted line in Fig. 1 and as shown in Fig. 5. Then, as forward movement of plunger 9 occurs, the plunger extension 68 will force the article and partially folded wrapper out of the receptacle in range with said plunger extension, and into the receiving channel 71. When this occurs, the portion of flap 72 projecting above the article 65 will take against the upper wall 96 of the receiving channel 71 causing the flap 72 to assume the position shown in Fig. 6. It will be evident that the paste 83 on flap 72 will cause the flap to adhere to the portion of wrapper 50 previously folded upon the article. The forward movement of plunger extension 68 forces the partially wrapped article to a position where end flaps 97 of the wrapper are in range with downwardly extending plates 98. Plates 98 are pivoted at 99 to a bar 100 which is secured to the vertically reciprocating rod 87. The vertical reciprocations of rod 87 occur during return movement of the plunger. The plates 98 are provided with upward extensions 101, and a spring 102 placed between said extensions forces them outward, causing the plates 98 to be moved inward toward each other. Plates 98 are curved inwardly, so that as they are moved down by means of vertical rod 87, their outwardly extending lower ends will first fold the flaps 97 around the upper corners of the article 65, and as the plates move farther down, the inward curvature of said plates will force the wrapper against the upper corner of the article, said spring 102 permitting necessary play of the plates on the pivots 99. Wrapper flaps 103 of said partially wrapped articles in the receiving channel are in range with intermittently rotating folders 104 and 105 which are secured to shafts 106 and 107 extending transversely above the receiving channel. Secured to the shaft 106 is a chain wheel 108 over which rides an endless chain 109 which also rides over a larger chain wheel 110 secured to shaft 58. The chain wheel 110 on shaft 58 is so proportioned to chain wheel 108 on shaft 106 that, when shaft 58 makes

one-sixth of a revolution, one complete revolution of shaft 106 will occur. Secured to shaft 106 is a gear wheel 111 in mesh with a gear wheel 112 which is secured to shaft 107, so that the intermittent revolutions imparted to shaft 106 by means of shaft 58, will be imparted to shaft 107, but in a reverse direction. When at rest, the folders 104 and 105 occupy the positions shown in Figs. 1, 2 and 12. When shafts 106 and 107 are rotated, said folders will travel in the directions indicated by the arrows shown in Fig. 12. Consequently, said folders will take against the wrapper flaps 103 of the partially wrapped article shown in Fig. 7, causing said flaps to be folded to the position shown in Fig. 8.

Repetition of the operation of the machine so far described, will cause articles having their wrappers folded to the position shown in Fig. 8, to be successively moved forward by succeeding partially wrapped articles.

Secured to shaft 106 is a chain wheel 113 over which rides an endless chain 114 which also rides over a chain wheel 115 secured to a shaft 116. Shaft 116 extends through paste receptacles 117 and has rollers 118 secured to it, which rollers revolve in paste 119 within the receptacles and carry said paste out through openings formed in the bottoms of said receptacles. Secured to shaft 116 is a gear wheel 120 in mesh with a gear wheel 121 which is secured to a shaft 122 extending transversely above the receiving channel 71. Secured to shaft 122 are segmental surfaces 123, which being rotated by shaft 122 and gears 120-121 from shaft 116, cause paste to be taken from rollers 118 and carried to and deposited upon a wrapper flap 124 of a partially wrapped article in said receiving channel, as is shown at 125 in Fig. 8. Receiving channel 71 is provided with stationary folders 126 which, during movement of said partially wrapped articles in said channel, cause the paste coated wrapper flaps 124 to be folded against the wrapped article, in the manner shown in Fig. 9.

Having described our invention, what we claim is:

1. A wrapping machine comprising intermittently moving chains carrying a series of receptacles adapted to receive partially wrapped articles; a receiving channel in range with one of said receptacles during the time said chains remain stationary, said receiving channel having a stationary folder; a plunger adapted for reciprocating movement through said receptacle in range with said receiving channel; means whereby paste is applied to a wrapper flap of a partially wrapped article in another one of said receptacles; a stationary folder adapted during the movement of said chains to take against said wrapper flap, whereby the

wrapper flap is folded and caused to rest between said stationary folder of the receiving channel and said receptacle in range therewith, forward movement of said plunger through said receptacle causing the partially wrapped article therein to be forced out and into said receiving channel, said wrapper flap during said movement of the partially wrapped article taking against said stationary folder of the receiving channel, whereby the wrapper flap is folded upon the wrapped article, said paste applied to said wrapper flap serving to hold the wrapper in place.

2. A wrapping machine comprising intermittently moving endless chains carrying a series of receptacles adapted to receive partially wrapped articles; a two-part plunger; one part thereof adapted for reciprocating movement in range with one of said receptacles and the second part of said plunger adapted for reciprocating movement through another one of said receptacles during the time said chains remain stationary, a receiving channel in range with the last named receptacle, said receiving channel having a stationary folder, means whereby paste is applied to a wrapper flap of a partially wrapped article in one of said receptacles; a stationary folder adapted during the movement of said chains to take against said wrapper flap whereby said wrapper flap is folded and caused to rest between said stationary folder of the receiving channel and the receptacle in range therewith, means whereby a partially wrapped article is forced by the first part of said plunger in said receptacle in range therewith, said second part of said plunger simultaneously moving through said receptacle in range therewith, whereby the partially wrapped article therein is forced out and into said receiving channel, said wrapper flap during movement of the partially wrapped article taking against said stationary folder of the receiving channel, whereby said wrapper flap is folded upon the wrapped article, said paste applied to said wrapper flap serving to hold the wrapper in place.

3. A wrapping machine comprising intermittently moving chains carrying a series of receptacles adapted to receive partially wrapped articles; a two-part plunger, one part thereof adapted for reciprocating movement in range with one of said receptacles, and the second part of said plunger adapted for reciprocating movement through another one of said receptacles during the time said chains remain stationary; a receiving channel in range with the last named receptacle, said receiving channel having a stationary folder; means whereby paste is applied to a wrapper flap of a partially wrapped article in one of said receptacles; a stationary folder adapted during the movement of said chains to take against a wrapper flap of a partially wrapped article in one of said receptacles, whereby said wrapper flap is partially folded upon the article, means whereby a partially wrapped article is forced by the first part of said plunger into said receptacle in range therewith, said second part of said plunger simultaneously moving through said receptacle in range therewith, whereby the partially wrapped article therein is forced out and into said receiving channel, said stationary folder of the receiving channel during said movement of the partially wrapped article, taking against said partially folded wrapper flap, whereby said wrapper flap is folded upon the partially wrapped article; a wrapper folding mechanism operating during return movement of said plunger and adapted to fold certain wrapper flaps of said partially wrapped article in said receiving channel, and a second wrapper folding mechanism, having intermittent movements for causing certain other wrapper flaps of said partially wrapped article in said receiving

to take against said wrapper flap whereby the wrapper flap is folded and caused to rest between said stationary folder of the receiving channel and the receptacle in range therewith; stationary folders between the first named receptacle and the first part of said plunger, means whereby an article and wrapper are forced by the first part of said plunger between said stationary folders, thereby causing the wrapper to be partially folded upon the article, said plunger also causing the partially wrapped article to be forced into said receptacle in range therewith, said second part of said plunger simultaneously moving through said receptacle in range therewith, whereby the partially wrapped article therein is forced out and into said receiving channel, said wrapper flap during said movement of the partially wrapped article taking against said stationary folder of the receiving channel, whereby said wrapper flap is folded upon the wrapped article, said paste applied to said wrapper flap serving to hold the wrapper in place.

4. A wrapping machine comprising endless chains carrying a series of receptacles adapted to receive partially wrapped articles, an intermittently moving mechanism for causing intermittent movements of said chains; a two-part plunger, one part thereof adapted for reciprocating movement in range with one of said receptacles and the second part of said plunger adapted for reciprocating movement through another one of said receptacles during the time said chains remain stationary; a receiving channel in range with the last named receptacle, said receiving channel having a stationary folder; a stationary folder adapted during the movement of said chains to take against a wrapper flap of a partially wrapped article in one of said receptacles, whereby said wrapper flap is partially folded upon the article, means whereby a partially wrapped article is forced by the first part of said plunger into said receptacle in range therewith, said second part of said plunger simultaneously moving through said receptacle in range therewith, whereby the partially wrapped article therein is forced out and into said receiving channel, said stationary folder of the receiving channel during said movement of the partially wrapped article, taking against said partially folded wrapper flap, whereby said wrapper flap is folded upon the partially wrapped article; a wrapper folding mechanism operating during return movement of said plunger and adapted to fold certain wrapper flaps of said partially wrapped article in said receiving channel, and a second wrapper folding mechanism, having intermittent movements for causing certain other wrapper flaps of said partially wrapped article in said receiving

channel to be folded, said second wrapper folding mechanism being actuated by said intermittently moving mechanism for causing intermittent movements of said chain.

5 5. A wrapping machine comprising intermittently moving chains carrying a series of receptacles adapted to receive partially wrapped articles, a receiving channel in range with one of said receptacles during the time said chains remain stationary, said receiving channel having a stationary folder; a plunger adapted for reciprocating movement through said receptacle in range with said receiving channel; a stationary folder adapted during the movement of said chains to take against a wrapper flap of a partially wrapped article in one of said receptacles, whereby said wrapper flap is folded and caused to rest between said stationary folder of the receiving channel and said receptacle in range therewith, forward movement of said plunger through said receptacle causing the partially wrapped article therein to be forced out and into said receiving channel, said wrapper flap during said movement of the partially wrapped article taking against said stationary folder of the receiving channel, whereby the wrapper flap is folded upon the partially wrapped article; and vertically reciprocating folders operating during return movement of said plunger and adapted to fold wrapper flaps of said partially wrapped article in said receiving channel, said folders consisting of spring pressed pivoted curved plates which serve to maintain pressure against the fold of said wrapper flap on said article, substantially as described.

6. A wrapping machine comprising a reciprocating plunger having two parts, one part thereof arranged tandem to the other part; intermittently moving chains carrying a series of receptacles adapted to receive partially wrapped articles; a stationary folder adapted during the movement of said chains to take against a wrapper flap of a partially wrapped article in one of said receptacles whereby said wrapper flap is partially folded upon the article; the part of said chains carrying said receptacle causing said receptacle to be in front of one part of said plunger when said chains come to rest; a receiving channel in range with said receptacle, said receiving channel having a stationary folder; means whereby another part of said chains causes another receptacle to be in front of the other part of said plunger when said chains come to rest; means whereby the last named part of said plunger causes a partially wrapped article to be forced into the last named receptacle, the first named part of said plunger simultaneously moving through said receptacle in front thereof, whereby the partially wrapped article therein is forced out and into said receiving channel, said stationary folder of the receiving channel during said movement of the partially wrapped article taking against said partially folded wrapper flap, whereby said wrapper flap is folded upon the wrapped article.

30 7. A wrapping machine comprising endless chains carrying a series of receptacles adapted to receive partially wrapped articles, means for causing intermittent movements of said chains; a receiving channel in range with one of said receptacles, a plunger adapted for reciprocating movement through said receptacle whereby a partially wrapped article in said receptacle is forced out and into said receiving channel; a wrapper folding mechanism and means for actuating it, whereby certain wrapper flaps of said partially wrapped article in said receiving channel are folded; mechanism for applying paste to a wrapper flap of a partially wrapped article in a receptacle succeeding the first named receptacle, said paste applying mechanism being actuated by said means for actuating said wrapper folding mechanism; a second wrapper folding mechanism, causing certain other wrapper flaps of said partially wrapped article in said receiving channel to be folded, said second wrapper folding mechanism being actuated by said means for causing intermittent movements of said chains; a stationary folder adapted during the movement of said chains to take against said paste coated wrapper flap of said succeeding partially wrapped article, whereby said wrapper flap is partially folded upon the wrapped article.

folded wrapper flap, whereby said wrapper flap is folded upon the wrapped article.

7. A wrapping machine comprising a reciprocating plunger having two parts, one part thereof arranged tandem to the other part; intermittently moving chains carrying a series of receptacles adapted to receive partially wrapped articles; a stationary folder adapted during the movement of said chains to take against a wrapper flap of a partially wrapped article in one of said receptacles whereby said wrapper flap is partially folded upon the article, the part of said chains carrying said receptacle causing said receptacle to be in front of one part of said plunger when said chains come to rest; a receiving channel in range with said receptacle, said receiving channel having a stationary folder; means whereby another part of said chains causes another receptacle to be in front of the other part of said plunger when said chains come to rest; means whereby the last named part of said plunger causes a partially wrapped article to be forced into the last named receptacle, the first named part of said plunger simultaneously moving through said receptacle in front thereof, whereby the partially wrapped article therein is forced out and into said receiving channel, said stationary folder of the receiving channel during said movement of the partially wrapped article taking against said partially folded wrapper flap, whereby said wrapper flap is folded upon the wrapped article.

100 8. A wrapping machine comprising endless chains carrying a series of receptacles adapted to receive partially wrapped articles, means for causing intermittent movements of said chains; a receiving channel in range with one of said receptacles, a plunger adapted for reciprocating movement through said receptacle whereby a partially wrapped article in said receptacle is forced out and into said receiving channel; a wrapper folding mechanism and means for actuating it, whereby certain wrapper flaps of said partially wrapped article in said receiving channel are folded; mechanism for applying paste to a wrapper flap of a partially wrapped article in a receptacle succeeding the first named receptacle, said paste applying mechanism being actuated by said means for actuating said wrapper folding mechanism; a second wrapper folding mechanism, causing certain other wrapper flaps of said partially wrapped article in said receiving channel to be folded, said second wrapper folding mechanism being actuated by said means for causing intermittent movements of said chains; a stationary folder adapted during the movement of said chains to take against said paste coated wrapper flap of said succeeding partially wrapped article, whereby said wrapper flap is partially folded upon the wrapped article.

ed upon the article, forward movement of said plunger through said succeeding receptacle causing the partially wrapped article therein to be forced out and into said receiving channel, said receiving channel having a stationary folder which during said movement of the succeeding partially wrapped article takes against said partially folded paste coated wrapper flap thereof, causing 10 said paste coated wrapper flap to be folded upon the wrapped article, said movement of the succeeding partially wrapped article causing the preceding wrapped article to be moved farther forward in said receiving 15 channel.

9. A wrapping machine comprising endless chains carrying a series of receptacles adapted to receive partially wrapped articles, means for causing intermittent movements of said chains; a receiving channel in range with one of said receptacles, a plunger adapted for reciprocating movement through said receptacle, whereby a 20 partially wrapped article in said receptacle is forced out and into said receiving channel, a wrapper folding mechanism adapted to fold certain wrapper flaps of said partially wrapped article in said receiving channel, a second wrapper folding mechanism, causing certain other wrapper flaps of said partially wrapped article in said receiving channel to be folded, said second wrapper folding mechanism being actuated by said means for causing intermittent 25 movements of said chains; a stationary folder adapted during the movement of said chains to take against a wrapper flap of a partially wrapped article in a receptacle 30 succeeding the first named receptacle, where- 35

by said wrapper flap is partially folded 40 upon the article, forward movement of said plunger through said succeeding receptacle causing the partially wrapped article therein to be forced out and into said receiving channel, said receiving channel having a stationary folder which during said movement of the succeeding partially wrapped article takes against said partially folded wrapper flap thereof, whereby said wrapper flap is folded upon the partially wrapped article, 45 said movement of the succeeding partially wrapped article causing the preceding partially wrapped article to be moved farther forward in said receiving channel, successive movement of said wrapper folding mechanisms, receptacles and plunger causing said preceding partially wrapped article to be successively moved farther forward in said receiving channel, mechanism for applying paste to certain wrapper flaps of said preceding partially wrapped article in said receiving channel, said paste applying mechanism being actuated by said means for actuating said means for causing intermittent movements of said chains; and a stationary 50 folder adapted during movement of said preceding partially wrapped article to fold said paste coated flaps thereof against the wrapped article, substantially as described. 55

Signed at New York city in the county 60 of New York and State of New York this 65 8th day of August, A. D. 1918.
